[57] **CLAIM**

The ornamental design for a square framed decorative calendar, as shown and described.

DESCRIPTION

FIG. 1 is a front perspective view of a square framed decorative calendar showing our new design;

FIG. 2 is a front elevational view;

FIG. 3 is a top plan view, the bottom view being identical thereto;

FIG. 4 is a rear elevational view; and,

FIG. 5 is a side elevational view, the opposite side being a mirror image thereof.
